ORE CONCENTRATOR

Filed Jan. 5, 1942

FIG. 1.

II ←

UNITED STATES PATENT OFFICE

2,366,223

ORE CONCENTRATOR

Berne Tocci-Guilbert, San Francisco, Calif.

Application January 5, 1942, Serial No. 425,610

2 Claims. (Cl. 209—455)

This invention relates to improvements in ore concentrators and more particularly to pulsatory hatches for separating fines suspended in flowing liquid.

Among the objects of the invention is the provision of a hatch in which the agitating of the water therein is localized.

Another object is the prevention of downward suction through the separating means in the upper portion of the hatch.

Another object is the provision of an auxiliary water supply into the hatch beneath the separating means.

Another object is to intermittently force the auxiliary water supply upward through the separating means.

Another object is the interposition of a separating means between the upward flow from below and the horizontal flow of water across the separating media in the hatch.

A further object is the provision of speed and volumetric control of the pulsating means.

Other objects and advantages will appear as the description progresses.

In this specification and the accompanying drawing the invention is disclosed in its application to ore concentration. But it is to be understood that it is not limited to this form; because it may be embodied in modifications for other uses within the spirit of the invention as defined in the claims following the description.

In the drawing:

Fig. 1 is a front elevation of a hatch and pulsating assembly constructed and diagrammatically combined in accordance with this invention. The hatch is broken away in vertical sections on the line I—I, Fig. 2, to disclose the structure of the pulsating assembly.

Fig. 2 is a side view of the same in vertical section on the line II—II, Fig. 1.

In this disclosure the term "material" is intended to more particularly define classified and menstruum suspended ores containing gold, silver, platinum and other values associated with quartz, gravel, and other base material either milled or found in a comminuted state in nature, colloquially known as "pay dirt."

It is customary to grade, classify and otherwise prepare the material before introducing into the concentrating hatch; different materials require different pretreatment.

The hatch has the boxlike upper portion 1, and the tapered lower portion 2, with the outlet gate 3 at the lower end. In the present instance the hatch is suspended within the surrounding

frame 4, on the alined trunnions 5, 6, engaging their respective bearings 7, 8, on the frame 4, for the purpose of leveling the hatch within the frame. The friction band 9 surrounding the trunnion 5 is fixed to the frame by the bolt 10. This band may be tightened by the nut 11 engaging the bolt 12 which passes through both ends of the band, to lock the hatch in leveled position in one plane. If conditions require, the frame 4 can be provided with similar trunnions such as 4', see dotted lines Fig. 1, and a locking means to level the frame 4 within another surrounding frame 4'', to level the hatch on the transverse plane. This in effect provides either a half or a full gimbal mounting, whereby the hatch may be leveled on uneven ground or on a mobile base. See my copending application of even date, entitled Mining machines and bearing Serial Number 425,609.

20 The hatch has the upper tier 13, hinged at 14, 14, to the upper edge of the hatch. The gasket 15, see Fig. 2, is interposed between the top edge of the hatch and the lower edge of the tier 13 and adapted to be compressed by the screw clamps 16, disposed at intervals around the hatch to make a watertight joint between the hatch and the superimposed tier. The bottom of the tier consists of the screen 17, located above the gasket level.

25 30 A series of compartments is formed above this screen by the bisecting partitions 18, 19, extending upwardly above the screen. The front end of the tier overhangs at 20, see Fig. 1, to receive the flowing material. The bottom of this overhang is provided with a block 21 of wood or the like for reducing the wear caused by the descending material.

The compartments above the screen 17 are filled with heavy pellets 22, preferably of steel, lead or the like, about $\frac{1}{8}$ of an inch in diameter. The incoming material flows across the tops of these pellets and the fines suspended therein descend into the interstices between the pellets, through the screen and into the sump formed by the lower portion of the hatch. The upper edges of the partitions and the pellets 18, 19 act as riffles in the flow of the material to facilitate the separation of the fines from the flowing gangue. The floated particles of gangue discharge into the inclined trough 23, for disposal at the side of the hatch. The concentrates descend into the lower portion 2 of the hatch.

35 The upper stratum of water in the hatch below the screen 17 is surged in an upward direction only. The pneumatic water displacing means

includes the casing 24, closed at both ends. This casing is located intermediate the upper boxlike portion 1 of the hutch immediately beneath the screen 17 and extends across the length of the hutch. The casing has the flanged head 25 bolted to the outside of the side of the hutch with an intervening gasket to prevent leakage. The opposite end has the inlet pipe 26 screwed therein and projecting through and sealed in a hole in the adjacent side wall of the hutch. The top angle of the casing 24 causes the descending concentrates to slide off the top of the casing.

The pipe 26 is screwed into the T fitting 27 behind the check valve 31, which is connected by the flexible hose 29 with a source of auxiliary liquid supply. The opposite end of the casing 24 has a similar inlet 30 screwed into the head 25 and the outlet from the check valve 31. The opposed auxiliary water inlets 26, 30, prevent the incoming liquid surging back and forth in the casing 24.

The incline planes of the top of the casing are provided with a series of outlet holes 33, 34, respectively, and located near the horizontal axis of the casing. These outlets are normally closed by the series of valves such as 35, 36, mounted upon springs 37, 38, fixed to the casing and urging the valves closed over the outlets 33, 34. The water flowing into the casing through the check valve 31, and the pipes 26, 30, unseats these valves 35, 36 and escapes upward through the screen 17 when the hutch is completely filled with water by the incoming flow of material above the pellets 22 and the auxiliary water supply.

The pneumatic pulsator 37 extends from end to end of the casing 24. It preferably consists of a flexible rubber tube having its outer end closed by being clamped around the plug 38 supported on the pin 38' fixed on the end of the casing. The inlet end of the tube is similarly clamped around the inlet nipple 39 extending through the head 25 of the casing. The pulsator tube 37 is enclosed within the perforated cylinder 37' and surrounds the perforated tube 37'' which limits its distension and contraction by the pump strokes. The flexible hose 40 connects the pulsator 37 with the air pump.

This pump preferably consists of the bellows 41 enclosed within a ventilated protective casing 42, which is mounted upon the standard 43 supported by the base 44, which may be part of the hutch support mounting 4. The bellows top has a flanged nipple 46 extending upward through the top of the casing 42 to which it is fixed. This nipple has the cross pipe fitting 47 connected with the hose 40 through which the bellows impulses are communicated to the pulsator 37. This fitting 47, has the flutter valve 48 for admitting atmospheric pressure to the bellows to prevent minus pressure in the bellows on the suction stroke. The spring set safety valve 50 in the fitting 47 provides for the release of excessive pressure in the bellows.

The lower end of the bellows 41 is attached to the plate 51 having the stem 52 slidable in the guide 53 on the standard 43. This stem is pivoted to the connecting rod 54, engaging the crank pin 55, adjustable in the slotted head 56, for varying the stroke of the bellows. This head 56 is driven by the motive change speed gearing 57 mounted on the base 44, for varying the impulse cycles of the bellows. This speed control combined with means for varying the displacement capacity of the bellows and the pul-

sator, acting upon the auxiliary water inflow is an important feature of this invention in adjusting it to the requirements of various materials being concentrated in the hutch.

5 The check valve 31 can be dispensed with when the head or weight of auxiliary liquid at 29 exceeds the force of the pulsator 37, enough to cause the liquid surge from the casing 24 to pass upward through the separating means 10 17-22.

Broadly stated the formula for accurate concentration and its governing physical law is: "Volume times density, times speed or power or both."

15 This invention operates substantially as follows: The inflow of material suspended in a fast flowing stream of liquid fill the hutch to a level an inch or so above the pellets 22. This is supplemented by the auxiliary supply of clear liquid through the inlets 26, 30, through the casing 24 and out, through the outlets 33, 34, and upward through the upper stratum of liquid in the hutch above the level of the casing 24, to mingle with the material rippling across the tops of the 20 pellets.

25 During the suction stroke of the bellows 41, the pulsator 37 contracts, during which interval the springs 38, 39, automatically close all the valves 35, 36 and permit the auxiliary water 30 supply through the hose 29 to completely fill the casing 24.

30 With the upstroke of the bellows 41 the flutter valve 48 and the check valve 31 both close when the pulsator 37 expands. This forcibly displaces water from the casing 24, which intermittently surges upward through the screen 17 and the interstices between the pellets 22, without lifting the pellets because of their weight and substantially spherical shape.

35 40 The detritus having more volume in proportion to density than the heavy or metallic particles, is lifted and "scalped" off by the velocity of the material flowing horizontally across the top of the pellets 22. The intervals between the 45 surge of the upwardly flowing liquid enable the natural precipitation of the heavier particles interspersed among the pellets. These particles having greater density in proportion to their volume descend, which is in accordance with the 50 above formula. The heavy interspersed pellets 22 act as a coarse separating medium, through which the auxiliary liquid supply 29 is always pulsated upwardly, while the heavy particles of material precipitate.

55 55 Particular attention is directed to the fact that after the first filling, the body of water in the hutch at no time moves downwardly with respect to the screen 17. Such a downward movement would tend to suck undesirable detritus 60 into the hutch.

65 The practice heretofore of pulsating the whole body of water in the hutch has been known to literally suck the impacted screen out of its frame. Such downward movement minimizes the concentrating effect. This disadvantage could not occur in the present invention.

70 When the screen 17 and pellets 22 become inefficient because of impacted matter or corrosion, the tier 13 can be swung on the hinges 14, upside down over a tray having a screen bottom of less mesh than the size of the pellets. The exposed screen 17 can be brushed free of obstructive matter and the pellets cleansed by attrition and flushing.

75 The quiescent or static body of water in the

hutch below the level of the pulsator casing 24, permits the undisturbed precipitation of float gold and other values suspended therein and having sufficient weight to sink when not supported by the power of agitated liquid.

The merit of the present invention is demonstrated in actual practice under field conditions, by the accumulated concentrates of precious metallic values in the hutch, associated with hematite, ferric oxides, black sand and other heavy particles; with only traces of silica, quartz and fine detritus. Tests of the discarded tailings show only traces of "colloidal" values too small to be separated by any mechanical means.

When the concentrates accumulate in the bottom 2 of the hutch to an obstructive extent, they are drawn off through the gate 3 into a tub, to be further processed by amalgamation, smelting or otherwise to save the metallic values.

It will be apparent to those skilled in the art that materials, other than auriferous ores and metallic particles suspended in menstruum, can be separated by this invention, according to their relative density and volume in accordance with the law governing concentration above cited.

Having thus described this invention, what is claimed and desired to secure by Letters Patent is:

1. A concentrator including a hutch having a static body of liquid in its lower portion; a tier attached to the upper portion of said hutch; a screen forming the bottom of said tier; a layer of relatively heavy pellets overlying said screen; an elongated closed casing in said hutch with its

5 top extending along the length of said hutch in proximity to said screen; outwardly opening check valves in the top of and sealing said casing from the body of water in said hutch and discharging outwardly from said casing and through said screen; means for directing a fast flowing stream of material across the top of said layer of pellets and maintaining a liquid level in said hutch and tier above said layer of pellets; and auxiliary means for ejecting an intermittent stream of liquid into said casing and through said check valves and upwardly through said screen without agitating said static body of liquid below said casing.

10 2. A concentrator including a hutch having a static body of liquid therein; a tier attached to the upper portion of said hutch; a screen forming the bottom of said tier; an elongated closed casing in said hutch with its top extending along the length of said hutch in proximity to said screen; outwardly opening check valves in the top of said casing and sealing it from the body of water in said hutch and discharging outwardly from said casing and through said screen; means for 15 directing a flowing stream of material through said tier above said screen and maintaining a liquid level in said hutch above said screen; an expansive and contractive pulsator extending the length of and within said casing; a reciprocating 20 pump discharging into said pulsator; a variable speed driving means for said pump; and means for varying the capacity of said pump.

BERNE TOCCI-GUILBERT.
